UNITED STATES PATENT OFFICE.

JAMES COURTHOPE PEACHE AND MARK HEATON ROBINSON, OF RUGBY, ENGLAND,
ASSIGNORS TO WILLANS & ROBINSON, LIMITED, OF RUGBY, ENGLAND.

INTERNAL-COMBUSTION ENGINE.

No. 921,649.

Specification of Letters Patent.

Patented May 11, 1909.

Application filed January 18, 1908. Serial No. 411,501.

To all whom it may concern:

Be it known that we, JAMES COURTHOPE PEACHE and MARK HEATON ROBINSON, engineers, subjects of the King of Great Britain, both residing at Victoria Works, Rugby, England, have invented new and useful Improvements in Internal-Combustion Engines, of which the following is a specification.

10. This invention relates to internal combustion engines working on the two-cycle system, *i. e.* a working stroke in which the gases are exhausted by means of ports formed in the sides of the cylinder and uncovered by 15 the piston toward the end of its stroke and in which a supply of scavenging air completes the expulsion of the exhaust gases during the period that these exhaust ports are uncovered and that fills the cylinder with a 20 charge of air. For obtaining the scavenging charge of air we as heretofore provide an annular air pump at the forward end of each working cylinder but according to this invention we provide a mechanically operated 25 valve for controlling the admission of air to and its delivery from each air pump. The air discharged from each air pump we pass into a receiver which is in connection with the rear end of each working cylinder through a 30 non-return valve. We also make provision for putting the inlet to each mechanically operated valve either in communication with the atmosphere for normal working or with a reservoir of compressed air for starting. 35 To allow of the engine being reversed we give motion to the above mentioned mechanically operated valve from a shaft, driven from the crank shaft by an intermediate shaft through gearing such that by 40 shifting the gear wheels on the intermediate shaft endwise the valve operating shaft is turned through an angle of 180° relatively to the crank shaft. This intermediate shaft we also employ for giving motion to a shaft 45 by which mechanism for injecting fuel at the proper time into the rear end of each working cylinder is operated and we make provision for giving a partial turn to this shaft when the intermediate shaft is shifted endwise so 50 that the injection of fuel may take place at the proper time in whichever direction the engine is being driven.

In the drawings annexed we have shown a multiple cylinder internal combustion engine

in which the above improvements are embodied.

Figure 1 is a front elevation and Fig. 2 is a vertical transverse section taken through one of the cylinders of the engine. Fig. 3 is an end elevation partly in section to show the reversing gear. Fig. 4 is a vertical section taken on the line *a*—*b* of Fig. 1.

a *a* are the working cylinders in each of which works a piston *b* which at its outer end has an enlargement *c* formed upon it to work in a corresponding enlargement *d* of the outer end of the cylinder *a*.

e is a connecting rod connecting the pistons *b* and *c* with a crank on the main crank shaft *f* of the engine.

g is a piston valve reciprocated to and fro past a port *h* opening into the inner end of the annular space between the cylinder *d* and piston *b*. One valve *g* is provided for each cylinder. The valve at the end of its up stroke leaves the port *h* open to an air inlet pipe *i* while at the end of its down stroke it closes the passage from the air inlet pipe to the port and opens a passage from the port to a compressed air receiver *j*. Each valve *g* is coupled by a connecting rod *k* to a crank on a shaft *l* which as shown in Fig. 3 is driven by helical tooth wheel gearing from an intermediate shaft *m* which is itself driven from the main crank shaft *f* by similar gearing. This shaft *l* extends from end to end of the engine and all the valves *g* are operated from it.

n is a non-return valve past which air under pressure can pass from the compressed air receiver *j* into the rear end of the working cylinder *a*. This non-return valve may be merely closed by a spring as shown and allowed to open when the pressure in the receiver is greater than in the working cylinder or the valve may be operated mechanically from some moving part of the engine.

m* is a passage connecting all the air receivers to one another so that together they form one common air receiver.

o is a fuel injecting mechanism for injecting fuel into the working cylinder. Any suitable mechanism for injecting fuel alone or fuel admixed with air may be used. In the arrangement shown the plunger of the injecting mechanism is operated by levers *p* coupled as shown in Fig. 2 to links *q* rocked by a connecting rod *r* to which an endwise

motion is given by a crank on a shaft *s* which by bevel wheel gear is driven from the intermediate shaft *m*.

t is a lever by which the helically toothed gear wheels on the shaft *m* can be moved endwise along this shaft for reversing the engine. By this endwise motion a partial turn, say a quarter turn, may be given to the intermediate shaft *m* and a consequent 10 quarter turn to the shaft *s* while a half turn is given to the valve shaft *l*. Or by otherwise proportioning the helical wheels any other desired amount of angular movement may be given to the fuel shaft *s* in conjunction with the 180° angular movement of the 15 scavenging shaft *l*.

u is an air pump driven by a crank on the main shaft *f* serving to compress air into a compressed air receiver *v*. From the receiver a pipe *w* extends to a port formed through the fixed casing of a valve or cock *x*, the plug of which is a tube *y* which extends along the center of the air supply passage *i*. The tube *y* has projections *z* extending from it which fit to the interior of the air supply passage *i*. When a partial turn is given to the tube *y* by the starting lever *y** and the projections *z* upon it are brought into position to shut off outer air from the air inlet to 20 the casing of the valves *g*, air can pass from the compressed air receiver into the tube *y* and through the hollow projections *z* to the valves *g*. When compressed air is thus supplied to the valves *g* the engine will be 25 started by the compressed air acting against the annular pistons of the air scavenging cylinders and the exhaust from the scavenging cylinders will perform its normal work of scavenging the working cylinders. In the 30 drawings the engine is arranged to work with a compression in the working cylinders sufficient to generate the heat required for igniting the fuel on injection. It can however be arranged for working with lower 35 compression and in that case any ordinary suitable ignition mechanism may be used.

What we claim is:—

1. The combination of a row of working cylinders each having an annular air pump 50 at its front end, a crank shaft driven from the pistons of these cylinders, an air receiver, a valve for controlling the admission of air to each air pump on the out-stroke of its piston and its discharge from the air pump into 55 the air receiver on its in-stroke, a shaft driven from the crank shaft extended along the row of cylinders, means for operating the air pump valves from this shaft, passages from the air receiver to the rear ends of all the 60 working cylinders, a non-return valve at the end of each passage and means for introducing fuel into the rear end of each cylinder independently of the air discharged into it from the receiver.

65 2. The combination of a working cylinder,

an annular air pump at its forward end, an air receiver, a valve for controlling the admission of air to the air pump on the out-stroke of its piston and its discharge from the air pump into the receiver on the in-stroke, means for operating this valve, a passage from the receiver to the rear end of the working cylinder, a non-return valve at the end of this passage, a second source of compressed air, and a valve by which the inlet to the air 70 pump valve can be placed in communication either with the atmosphere or with this second source of compressed air so that the engine may be started by the compressed air 75 acting against the air pump piston while the 80 exhaust from the air pump performs its normal work of scavenging the working cylinder.

3. The combination of a working cylinder, an annular air pump at its forward end, a 85 crank shaft driven from the piston of the working cylinder, an air receiver, a valve for controlling the admission of air to the air pump on the out-stroke and its discharge from the air pump into the air receiver on the 90 in-stroke, a shaft from which the valve is operated, an intermediate shaft lying in a plane at right angles to this valve operating shaft and the crank shaft, helical toothed wheel 95 gearing coupling the intermediate shaft with the other two shafts, and means for shifting the helical toothed wheels on the intermediate shaft endwise to reverse the engine.

4. The combination of a working cylinder, an annular air pump at its forward end, an 100 air receiver, a valve for controlling the admission of air to the air pump on the out-stroke and its discharge from the air pump into the receiver on the in-stroke, a crank shaft, a shaft from which the valve is operated, means for driving this shaft from the 105 crank shaft, a second shaft driven from the crank shaft, and means for delivering fuel to the rear end of the working cylinder operated by this second shaft.

5. The combination of a working cylinder, an annular air pump at its forward end, a crank shaft connected with the piston of this cylinder, an air receiver, a valve for controlling the admission of air to the air pump on the out-stroke and its discharge from the air pump into the receiver on the in-stroke, a shaft from which the valve is operated, an intermediate shaft lying in a plane at right angles to the valve operating shaft and the crank shaft, helical toothed wheel 115 gearing coupling the intermediate shaft with the two other shafts, means for shifting the helical gear wheels on the intermediate shaft endwise to reverse the engine, a second shaft 120 driven from the intermediate shaft, and means for delivering fuel to the rear end of the working cylinder operated by this shaft.

6. The combination of a row of working cylinders each having an annular air pump 130

at its front end, a crank shaft driven from the pistons of these cylinders, an air receiver, a valve for controlling the admission of air to each air pump on the out-stroke and its discharge from the air pump into the receiver on the in-stroke, a shaft extending along the row of cylinders, means for operating the valves of the several air pumps from this shaft, an intermediate shaft lying in a plane at right angles to this shaft and to the crank shaft, helical toothed wheel gearing coupling the intermediate shaft with the other two shafts, means for shifting the helical gear wheels on the intermediate shaft endwise to reverse the engine, means for delivering fuel to the rear ends of the working cylinders, and a second shaft driven from the intermediate shaft operating the fuel supplying means.

7. The combination of a row of working cylinders each having an annular air pump at its front end, a crank shaft driven from the pistons of these cylinders, an air receiver, a valve for controlling the admission of air to each air pump on the out-stroke and its dis-

charge from the air pump into the receiver on the in-stroke, a shaft extending along the row of cylinders, means for operating the valves of the several air pumps from this shaft, an intermediate shaft lying in a plane at right angles to this shaft and to the crank shaft, helical toothed wheel gearing coupling the intermediate shaft with the other two shafts, means for shifting the helical gear wheels on the intermediate shaft endwise to reverse the engine, means for delivering fuel to the rear ends of the working cylinders, a second shaft driven from the intermediate shaft operating these means, a second source of compressed air and valves by which the air inlet valves to the several air pumps can be placed either in communication with the atmosphere or with this second source of compressed air.
